DESIGN FOR AN ACCORDION

Carl E. Jacoby, Chicago, Ill., assignor to C. G. Conn, Ltd., Elkhart, Ind., a corporation of Indiana

Application January 19, 1938, Serial No. 74,400

Term of patent 7 years

To all whom it may concern:

Be it known that I, Carl E. Jacoby, a citizen of the United States, residing at Chicago, in the county of Cook and State of Illinois, have invented a new, original, and ornamental Design for an Accordion, of which the following is a specification, reference being had to the accompanying drawing, forming part thereof.

I claim:

The ornamental design for an accordion, substantially as shown.

CARL E. JACOBY.
